UNITED STATES PATENT OFFICE.

CHARLES J. WOHL, OF EL PASO, TEXAS.

TICKET-HOLDER.

1,093,517.

Specification of Letters Patent. Patented Apr. 14, 1914.

Application filed June 20, 1913. Serial No. 774,925.

To all whom it may concern:

Be it known that I, CHARLES J. WOHL, a citizen of the United States, residing at El Paso, in the county of El Paso and State 5 of Texas, have invented new and useful Improvements in Ticket-Holders, of which the following is a specification.

This invention relates to ticket holders, and particularly to a device for holding car 10 tickets; and it has for its primary object the provision of a receptacle for containing the tickets and means for effecting a positive single delivery of the tickets.

With the above and other objects in view, 15 the invention consists of certain novel features of construction, combination and arrangement of parts, as will be hereinafter described and claimed.

In the accompanying drawings:—Figure 20 1 is a perspective view of the device; Fig. 2 is an inverted perspective view thereof; Fig. 3 is a transverse section therethrough; and Fig. 4 is a longitudinal section therethrough.

25 The device comprises a receptacle 1, which is provided with a main permanent bottom 2, a false bottom 3, side walls 4 and connecting end walls 5. One of the side walls is provided along its upper longitudinal 30 edge with hinge knuckles 6 that are alined with similar hinge-knuckles 7 on a closure 8. A hinge pin 9 is extended through the alined knuckles so as to furnish a pivotal support for the closure whereby the latter 35 may be readily swung to open or closed positions. The opposite wall 4 has struck therefrom a resilient keeper 10, which is adapted to be projected into a keeper recess 11 in the flange 12 of the closure 8, 40 whereby to hold the latter against opening accidentally.

The supplemental bottom 3 is provided along one of its sides with a vertical wall 13 having a flange 14, which may be soldered or otherwise secured to the adjacent wall 4 of the receptacle. In this manner the wall 13 is spaced from the adjacent wall for a purpose to be hereinafter explained. At the opposite side, the bottom 3 is curved 50 downwardly and forwardly, as at 15, and it is soldered to the extension 16 of the main bottom. By curving the portion 15 as described the supplemental bottom is maintained in spaced relation to the main bottom 55 so as to accommodate in the intervening space therebetween a slidable ejector 17.

This ejector is provided with angularly-bent ends 18 and 19, the former being terminally extended through a slot 18^a in the bottom 3 and above the supplemental bottom 60 for a distance equal to the single thickness of the tickets. Normally the portion 18 lies in the space between the wall 13 of the supplemental bottom and the adjacent wall 4 of the receptacle so that the ticket space 65 20 of the receptacle is uninterrupted to permit the tickets to be held in a flat condition upon the supplemental bottom where they may be singly engaged by the portion 18 when the ejector is moved in one direction. 70 The opposite side wall 4 is provided with a discharge slot 21, through which the tickets may be discharged as will be understood. The branch 19 is extended through a slot 22 in the main bottom. Said portion 19 is 75 provided beneath the slot 22 with a finger engaging button 24 which may be engaged with the finger and which is adapted when pressure is applied thereto to cause the ejector 17 to be advanced against the tickets 80 and in the direction of the discharge slot 21. A follower plate 25 is mounted to slide freely in the ticket space 20 and as illustrated said follower carries a spring 26 which has one of its ends freely engaged 85 against the closure 8 so that under the action of the spring the follower is yieldingly held against the tickets.

From the foregoing description, taken in connection with the accompanying drawings, the construction and operation of the invention will be readily understood without requiring a more extended explanation.

Various changes in the form, proportion and the minor details of construction may 90 be resorted to without departing from the principle or sacrificing any of the advantages of this invention as claimed.

Having thus described my invention, what I claim is:—

A ticket holder comprising a receptacle having a discharge slot, said receptacle having a double-walled side and a double-walled bottom, both walls of the bottom having slots therein respectively extending in opposite directions, an ejector slideable in the space between the walls of said bottom and having a ticket engaging projection extending through the slot in one wall of the bottom and into the receptacle and movable in the direction of the discharge slot, one wall of said double walled

side having a passage for receiving the projection whereby the latter may be disposed between both walls of said double-walled side on one adjusted position of the ejector, 5 a manipulating portion formed on the ejector and extending through the slot in the other wall of the bottom and a follower mounted in the receptacle and movable in the direction of said double walled bottom

and operable to hold the tickets in the path 10 of discharge movement of the ejector.

In testimony whereof I affix my signature in presence of two witnesses.

CHARLES J. WOHL.
